UNITED STATES PATENT OFFICE.

FRANK W. VAN NESS, OF MILWAUKEE, WISCONSIN, ASSIGNOR TO FRANK J. MATCHETTE, OF MILWAUKEE, WISCONSIN.

LUBRICATING SYSTEM AND APPARATUS.

1,019,103.

Specification of Letters Patent.

Patented Mar. 5, 1912.

Application filed May 2, 1910. Serial No. 558,812.

To all whom it may concern:

Be it known that I, FRANK W. VAN NESS, a citizen of the United States, residing at Milwaukee, in the county of Milwaukee, 5 and State of Wisconsin, have invented certain new and useful Improvements in Lubricating Systems and Apparatus, of which the following is a specification, reference being had to the accompanying drawing, 10 forming a part thereof.

This invention relates to lubricating systems and apparatus therefor, and the object of the invention is to provide a lubricating system and apparatus therefor whereby oil 15 or other fluid lubricant is supplied to the parts to be lubricated as the result of differences of pressures existing at the source or sources of supply of the lubricant and the place or places of use.

20 While the lubricating system and apparatus therefor described in this specification are capable of use in combination with different kinds of apparatus, they are of especial utility in combination with air or 25 gas pumping or moving devices and for simplicity of description and clearness of illustration the invention is illustrated and described as combined with vacuum cleaning apparatus and devices without any in- 30 tention, however, of limiting the invention solely to such a combination.

Additional objects of the invention are to provide arrangements of apparatus whereby the lubricant (hereinafter referred 35 to as "oil" for the sake of brevity) is supplied as the direct result of the operation of the apparatus to be lubricated so that oil is supplied automatically whenever the apparatus is put in operation and the supply of 40 oil stops when the apparatus is stopped or is otherwise relieved from duty, to arrange the apparatus, if desired, so that when oil is not being supplied from the main source of supply there will be a reserve supply of 45 oil for some parts of the apparatus, to so arrange the apparatus that the flow of oil can be readily controlled and proportioned so that neither flooding nor drying will occur, to so arrange the apparatus that oil will be 50 supplied from a reservoir or source of supply to the parts to be lubricated and will

then be returned to said reservoir for use over and over again in a continuous cycle and to so arrange the apparatus that only clean oil will be supplied to the parts to be 55 lubricated.

Referring to the drawings which accompany this specification and form a part thereof, on which drawings the same reference characters are used to designate the 60 same elements wherever they may appear in each of the several views and which drawings illustrate an embodiment of this invention, Figure 1 is a plan view of a vacuum cleaning plant; Fig. 2 is an elevation of the 65 plant looking in the direction of the arrow marked *a* Fig. 1; Fig. 3 is an elevation of the plant looking in the direction of the arrow marked *b* Fig. 1, the motor being omitted for clearness of illustration; Fig. 4 70 is a vertical section on an enlarged scale of the combined oil reservoir, separator and muffler taken on the line *c*—*c*, Fig. 1, and shows some of the associated parts; and Fig. 5 is a plan view of a detail. 75

Referring specifically to the drawings, the reference numeral 1 designates a base upon which the plant is mounted, 2 an electric motor, 3 a vacuum pump connected with and adapted to be driven by said motor, 80 4 a stand pipe through which the air and dirt are drawn, 5 a dirt and dust separator supported by columns 6, 7 a removable dirt and dust receptacle, 8 and 9 inlet pipes affording communication between separator 5 and 85 vacuum or exhausting pump 3, 10 an unloading valve, 11 discharge pipe from the pump, 12 a combined oil reservoir, oil separator and muffler, 13 exhaust pipe and 14 by-pass pipe. The function of unloading 90 valve 10 is to place pipe 9 in communication with pipe 8 or to cut off such communication and place pipe 9 in communication with by-pass pipe 14 when a sufficient intensity of vacuum is established in separator 95 5 so as to relieve the load on the motor 2. The vacuum pump 3 is a positive displacement pump of a well known, rotary type and has bearings 15 and 16 at its ends which require lubrication. The pump 3 also requires lubrication in its interior. 100

The discharge pipe 11 from the pump

communicates with a centrifugal spiral pipe 17 extending from bottom closure 160 up into the combined oil reservoir, oil separator and muffler 12 and its open, upper 5 extremity is preferably disposed in a horizontal plane and has its end cut off at an angle as clearly shown by Figs. 4 and 5 of the drawings. This construction gives the air and oil, and whatever dirt may be dis-
 10 charged therewith, a whirling motion in separator 12 and causes separation in the well known manner. Separation is also as-
 15 sisted because the large volume of separator 12 as compared with spiral 17 causes a de-
 creased velocity of flow of the air and fur-
 thermore the beveled end of spiral 17 per-
 mits a reduction of the velocity of flow of
 20 the air into the separator from pipe 17 by providing an enlarged area for the expan-
 sion and escape of the air from spiral 17. The exhaust pipe 13 is larger than inlet pipe 9 and discharge pipe 11 so that the per-
 25 iodic discharges of air from the pump 3 are merged as the result of the reservoir ac-
 30 tion of separator and muffler 12 causing a steady and comparatively noiseless exhaust through exhaust pipe 13. The pressure ex-
 35 isting in separator 12 is, of course, always as high as atmospheric pressure and the ex-
 40 cess pressure existing in separator 12 over the lower pressures which may exist in other parts of the apparatus is utilized to feed the lubricating oil.

The lower part of separator 12 is utilized 35 for an oil receptacle to hold a large quantity of oil so that frequent replenishing will not be necessary. A sight tube or oil gage 19 is in communication with the interior of separator 12 by means of a pipe 20 placed 40 near the bottom of the separator and below a downwardly extending partition 22 therein and also by means of a pipe 21 located above said partition 22. Tube 19 is provided with a screw cap 23 which may be 45 removed to allow oil to be poured into the oil reservoir. A pipe 24 leads from reser-
 50 voir 12 at a point below partition 22 and preferably closely adjacent to the upper part thereof, as shown, and from pipe 24 depends pipe 25 from which pipes 26 and 27 lead to the pump bearings 16 and 15 re-
 55 spectively to supply said bearings with oil. A pipe 28 extends upwardly from pipe 24, is then bent downwardly and communicates 60 with the interior of inlet pipe 9 at a point higher than pipe 24 to prevent siphoning. Valves 29 and 30 permit the quantity of oil flowing through pipes 28 and 25 to be regu-
 65 lated and a sight drop oil feed 31 is placed in pipe 28 so that the flow of oil can be readily observed and its quantity adjusted and proportioned by means of valve 29. A well 32 is provided in the bottom of the reservoir 12 to retain heavy particles dis-
 charged by the pump as scale from the

pipes, etc., and a draw off cock 33 is pro-
 70 vided for emptying the well 32 and reser-
 75 voir.

In the operation of the apparatus prac-
 75 tically all the dirt and dust is separated
 from the air in the separator 5, but a mi-
 nute quantity of dust in the form of impal-
 80 pable powder may be carried through the
 pump and discharged with the oily air into
 85 separator 12. Such dust will accumulate
 on the surface of the oil in the reservoir as a
 90 scum while any heavy particles such as
 pieces of scale, etc., which may find their
 way into separator 12 will sink through the
 95 oil and collect in well 32.

The function and operation of the system
 and apparatus illustrated by the drawings
 is as follows: The cap 23 is removed and oil
 100 poured into the reservoir until it fills the
 reservoir to say the line *d-d*, Fig. 4. The
 cap is then replaced. When the pump 3 is
 in operation a partial vacuum is created in
 pipe 9 (except when valve 10 is in its un-
 105 loading position, or the position which cuts
 off communication between pipes 8 and 9
 and establishes communication between
 pipes 9 and 14) and the greater air pressure
 existing in separator 12 will force the oil
 110 level inside of partition 22 down and the
 oil level outside the partition up, the parti-
 115 tion 22 having an opening 34 in its bottom.
 For convenience the space between partition
 22 and the shell of separator and reservoir
 120 12 will be termed the oil supply chamber
 and is designated by the numeral 35, and the
 space inside the partition 22 will be
 termed the scum chamber and is designated
 by the numeral 36.

The difference between the level of the
 105 oil in oil supply chamber 35 and the level
 of the oil inside of partition 22 depends
 upon the specific gravity of the oil and the
 difference between the air pressures existing
 in pipe 9 and separator 12, but this dif-
 110 ference of pressure is sufficient to raise the
 oil level in oil supply chamber 35 so that
 the oil will flow out through pipe 24 and
 will then flow by gravity through pipes 25,
 26 and 27 to bearings 15 and 16 of the
 115 pump 3. The quantity of oil flowing
 through pipe 25 is regulated by valve 30 for
 two reasons, first, so as not to supply an un-
 necessarily large quantity of oil to bearings
 15 and 16, and second, so that all the oil
 120 which flows through pipe 24 will not flow
 away by gravity through pipe 25 as it is de-
 sirable to introduce some oil for lubrication
 into the interior of the pump, preferably by
 mixing oil with the air entering the pump
 through supply pipe 9. Pipe 28 is made of
 sufficient length, say 18 inches, so that the su-
 perior air pressure in reservoir 12 over the
 air pressure in pipe 9 will raise the oil to
 the bend at the top of pipe 28 so that the
 oil will flow up through said pipe, through
 130

the top bend thereof and down into pipe 9. As a very small quantity of oil is required for lubricating the interior of the pump, when the oil is mixed with the air as shown 5 and described, valve 29 and sight drop feed 31 make it easy to properly adjust and proportion the supply.

As the surface of the oil in scum chamber 36, or inside of partition 22, is never intended to go as far down as aperture 34 10 (except when drain cock 33 is opened to drain the oil, etc., from the reservoir), partition 22 is in function and effect a means to strain the oil so that the scum on the top 15 of the oil cannot reach pipe 24 and only clean oil can get to the bearings and pump.

The lower part of the reservoir 12 is shaped like the frustum of a cone and partition 22 is similarly shaped and parallel 20 therewith and projects from the cylindrical side of reservoir 12 a short distance above the frustum-shaped, lower part. The effect of this construction is that the space within the oil chamber 35 above the line $d-d$, 25 contracts upwardly, while the space in scum chamber 36, or within partition 22, contracts downwardly, so that only a small excess of oil will fill chamber 35 and only a small quantity of oil will be necessary 30 within scum chamber 36 to seal the opening 34 at the bottom thereof.

The oil which enters the pump through inlet pipe 9, and the oil which seeps into the pump from the bearings 15 and 16, is 35 discharged into the separator 12, where it is separated from the air and is circulated over and over again in a continuous cycle, but it is only circulated when a difference exists between the pressures existing in the 40 separator 12 and the part of the vacuum system, as for example, pipe 9, with which pipe 28 communicates.

It will be readily seen that oil is supplied to the interior of pump 3 only when 45 the pump is creating or maintaining a vacuum or partial vacuum in pipe 9 and that when pipes 25, 26 and 27 have once been filled with oil, they contain a reserve supply of oil which will lubricate the bearings 15 50 and 16 of the pump 3, even though the vacuum is broken in pipe 9 by the unloading valve 10, or from some other cause, and the oil level in oil chamber 35 falls below pipe 24.

55 What is claimed is:

1. The combination with a vacuum system of a pump for creating a vacuum therein, an oil supply chamber the upper part of which is in communication with the vacuum system, and an oil reservoir which is in 60 communication with said oil supply chamber and in which reservoir the oil is subjected to a greater pressure than the pressure which exists in the vacuum system when 65 the pump is in operation.

2. The combination with a vacuum system of a pump for creating a vacuum therein, an oil supply chamber the upper part of which is closed, an oil reservoir which is in communication with the lower part of said oil supply chamber, and a pipe extending upwardly from said oil supply chamber and in communication with the vacuum system. 70

3. The combination with a vacuum system of a pump, provided with bearings, for 75 creating a vacuum therein, an oil supply chamber the upper part of which is in communication with the vacuum system, an oil reservoir which is in communication with the lower part of said oil supply chamber and in 80 which reservoir the oil is subjected to a greater pressure than the pressure which exists in the vacuum system when the pump is in operation, and a pipe leading from the upper part of said oil supply chamber to 85 supply oil to the bearings of the pump whereby the flow of oil from said oil supply chamber to said pipe is automatically established whenever a vacuum is created in the vacuum system and is stopped when the 90 vacuum in the system is broken.

4. The combination with a vacuum system of a pump, provided with bearings, for creating a vacuum therein, an oil supply chamber the upper part of which is in communication with the vacuum system, an oil reservoir which is in communication with the lower part of said oil supply chamber and in 95 which reservoir the oil is subjected to a greater pressure than the pressure which exists in the vacuum system when the pump is in operation, and a pipe leading from the upper part of said oil supply chamber and extending downwardly to the pump bearings whereby the flow of oil from said oil supply chamber to said pipe is automatically 100 established whenever a vacuum is created in the vacuum system and is stopped when the vacuum in the system is broken and whereby a reserve supply of oil will be 105 retained in said downwardly extending pipe when the flow of oil thereinto is stopped. 110

5. The combination with a vacuum system of a pump for creating a vacuum therein, an oil supply chamber the upper part of which is closed, an oil reservoir which is in communication with the lower part of said oil supply chamber and in which reservoir the oil is subjected to a greater pressure than the pressure which exists in the vacuum system when the pump is in operation, and a pipe extending upwardly from said oil supply chamber and then downwardly and communicating with the vacuum system at a higher point than it communicates with the 115 oil supply chamber. 120

6. The combination with a vacuum system of a pump for creating a vacuum therein, an oil reservoir into which said pump exhausts, an oil supply chamber in commu- 125 130

nication with said oil reservoir at its lower end and a communication from said oil supply chamber to said vacuum system whereby the oil supplied to said system and pump is used again in a continuous cycle.

7. The combination with a vacuum system of a pump for creating a vacuum therein, a combined oil separator and exhaust muffler into which said pump exhausts, said 10 separator being provided on the interior thereof with a depending partition forming an oil reservoir and scum chamber and a clean oil supply chamber, said separator

being in communication with the atmosphere whereby the oil in said oil reservoir and scum chamber is exposed to a pressure at least as high as atmospheric, and a communication between said clean oil supply chamber and the vacuum system.

In witness whereof I hereto affix my signature in the presence of two witnesses.
